HELEN SARGENT HITCHCOCK

BY

W. J. Eniss
ATTORNEY

UNITED STATES PATENT OFFICE.

HELEN SARGENT HITCHCOCK, OF NEW YORK, N. Y.

TOY ANIMAL.

Application filed August 28, 1925. Serial No. 53,066.

My invention relates to toys, and more particularly to representations of animals as playthings for small children.

An object of my invention is to produce a form, in wood, metal or other suitable materials, applicable to the simulation of a wide variety of animal types.

Another object of my invention is to form, from a combination of flat pieces of wood or similar materials representations of familiar animals and the like familiar postures and actions of said animals.

A further object of my invention is to form from flat pieces of suitable materials 15 toy animals articulated to simulate any one of a plurality of classes or varieties thereof, and also familiar postures and actions of the animal suggested thereby.

In the drawings illustrative of an embodiment of my invention,

Figure 1 is a front elevation of a toy representation of a familiar quadruped, simulating a type of elephant;

Figs. 2 and 3 are respective side elevation 25 and top plan view of the device shown in Fig. 1; and

Fig. 4 is a perspective view of the animal representation shown in Figs. 1, 2 and 3.

Having reference to the drawings, the 30 numeral 1 represents a toy elephant comprising the vertically disposed flat representation of the torso or body portion which in turn is attached to the similarly formed front portion 5 which will hereinafter be 35 referred to as the fore-quarters, and the rear part or hind-quarters 10, by means of tongue and groove joints comprising the tongues 2 projecting from the respective front and rearward edges of the torso and the grooves 40 3, transversely formed in the several members articulated therewith.

The torso 1 has its top and bottom edges shaped suggestively to represent respectively the back and belly lines of the animal, the 45 corresponding front and rear edges being substantially straight and, in the embodiment now being described, parallel.

The joinder of articulated members is completed by means of a straight pin 4 pass-

ing through aligned holes 4^a in the tongue and grooved members respectively, (shown in Fig. 1 in dotted lines), the pin held singly as in a driving bit in either or both the tongue or groove members.

When desired the tongue 2 may be formed of sufficient length to pass entirely through one of the flat members, as shown in Figs. 2 and 3, and projecting sufficiently to have its jointed connection with a third member. Thus in forming the toy elephant the 60 animal's trunk 7 is articulated to the trunk 2, extending through the thickness of the portion 5 representing the animal's forequarter 5. Similarly the elephant's tail 16 is attached to a tongue 2, extending through the piece 65 15 supplying the hind-quarters of the toy animal.

The elephant's ears 6 being conspicuous features of the forward members of the animal, are in the toy composed of the same 70 flat materials of which the other parts of the animal representation are made, and to make them relatively movable as in life, they are attached to the head of the member 5 by means of the tongue 2, groove 3 and pin 4 is the same manner as the trunk and tail are attached to permit of limited 75 oscillatory movements of those parts.

In following the same type of construction practically every species of quadruped may be simulated with a degree of likeness of suggestiveness that meets every requirement of a child's imaginative mind.

I claim:

A toy elephant having a vertically disposed flat torso member and vertically disposed hind and fore-quarters substantially at right angles thereto, tongues projecting from said member into and through openings in said respective fore-quarters and hind-quarters, a trunk member pivotally articulated to a tongue piercing said fore-quarter and a tail piece articulated to a tongue penetrating said hind-quarters.

In testimony whereof I have hereunto 85 set my hand.

HELEN SARGENT HITCHCOCK.
